UNITED STATES PATENT OFFICE.

PHILIPP LENZE, OF DÜREN, GERMANY.

LIGHTING APPARATUS FOR GAS-BURNERS.

SPECIFICATION forming part of Letters Patent No. 674,064, dated May 14, 1901.

Application filed June 20, 1900. Serial No. 20,964. (No model.)

To all whom it may concern:

Be it known that I, PHILIPP LENZE, a subject of the German Emperor, residing at Düren, Rhineland, Germany, have invented certain new and useful Improvements in Lighting Apparatus for Gas-Burners, of which the following is a specification.

My invention relates to that type of gas-burners in which a small constantly-burning jet is maintained for the purpose of igniting the larger illuminating-jet when the latter is turned on; and it consists in the features hereinafter described and claimed.

In the drawings, Figure 1 is a side elevation of a burner embodying my invention; Fig. 2, a vertical central section therethrough; Fig. 3, an enlarged top plan view of the burner; Figs. 4 and 5, enlarged detail sections on the correspondingly-numbered lines 20 in the second figure; Fig. 6, a section on the line 6 6 of said second figure. Figs. 7 and 8 are enlarged details on sections following the section of Fig. 2. Fig. 9 is a sectional view similar to Fig. 8, but showing the valve and 25 its float in position to close the gas-passage.

A represents a cylindrical outer casing closed by a base B and a cap C, the latter of which carries a bottomless depending cylinder C' within and concentric with the outer 30 casing and reaching nearly to, but not touching, the base thereof, so as to be sealed by the fluid contents D of said casing. Since the cylinder C' is of less diameter than the casing A, two chambers are formed within 35 the latter, an annular outer or pressure chamber d, included between the walls of said casing and cylinder, and an inner concentric gas-chamber d', embraced by the surrounding wall of the cylinder.

40 Into the gas-chamber enters a gas-pipe E through base B and rises to a point near the top of said chamber, where it terminates in a perforated head e, over which sits a valve E' for regulating or shutting off the flow of 45 gas. From the head e an igniting-tube F in constant communication with pipe E rises centrally through cap C and chamber f therein and discharges through nipple f' on screw-cap F', closing said chamber, into the lower 50 end of the aerating-tube G, having ventilating-openings g immediately at such point and

discharge-openings g' at its upper end, at which an igniting-flame is maintained above the lamp-burner H and centrally thereof, so that gas reaching said burner through the 55 housing H' may at once be lighted.

The valve E' is guided vertically by the aforesaid igniting-tube F or by a hub i, rising from the perforated head e and serving for the attachment of said tube, and is connected by rods i' with an annular float I, normally resting on the liquid in the gas-chamber and following its fluctuations. When the float rises, the valve is lifted off its seat, permitting the flow of gas into the chamber 65 d', whence it is led through ducts k into the chamber f, escaping therefrom through perforations k' into the base of the housing H', where it is aerated from openings l and then rises to the burner.

70 M is a pressure-pipe connecting with a source of pressure-supply and opening into the casing near the top of the pressure-chamber, so that the pressure in the latter may be increased at will or otherwise to raise the 75 level of the liquid in the gas-chamber, and thereby open the gas-valve therein.

The upper ends of the rods i may project beyond the valve, as represented in Fig. 8, to serve as stops to prevent it from rising so 80 far as to close the ducts k. Consequently the height to which the float will rise is limited, and it may sometimes be temporarily submerged in the pressure fluid, as indicated in Fig. 2, while the normal equilibrium is being regained.

85 It will be observed that by the above construction the igniting-tube is wholly contained within the body of the lamp and in constant connection with the head of gas and 90 that the gas for the illuminating-flame is led to the burner along practically the same path, but outside of and, in effect, concentrically with said igniting-tube.

I claim—

95 1. The combination of the annular outer pressure-chamber, the inner concentric gas-chamber opening below into the pressure-chamber, the gas-pipe rising within the gas-chamber and having ports in its crown, the 100 valve arranged to close said ports, the float by which said valve is controlled, the burner,

and the central igniting-tube extending from the crown of the gas-pipe through the valve and upward toward the burner.

2. The combination with the pressure-chamber and the inclosed gas-chamber, and float-supported valve in the latter, of the gas-pipe controlled by said valve, the burner and the perforated housing leading thereto, the central igniting - tube extending from the 10 crown of the gas-pipe through the valve and upward to the base of said housing, and the aerating-tube receiving from said igniting-tube and rising to the center of the burner.

3. The combination with the burner, of the 15 pressure-chamber *d*, the gas-chamber *d'* inclosed thereby and opening thereinto at the base, the gas-pipe *E* with its perforated head, discharging into the upper part of the gas-chamber, the valve *E'* for regulating the flow

from said pipe into said gas-chamber, the annular float *I* supporting said valve, the igniting - tube *F* leading from the gas - pipe through the crown of the gas-chamber and connecting with the burner, the chamber *f* surrounding said igniting - tube, the ducts 25 communicating between said chamber *f* and the crown of the gas-chamber, the aerating-tube *G* forming the connection between the igniting-tube and the burner, and the perforated housing *H'* forming the connection between the chamber *f* and said burner. 30

In testimony whereof I affix my signature in presence of two witnesses.

PHILIPP LENZE.
